UNITED STATES PATENT OFFICE.

ISAAC S. WACHOB, OF SCRANTON, PENNSYLVANIA.

DESIGN FOR SCHOOL-FURNITURE.

Specification forming part of Design No. 5,973, dated July 2, 1872.

Specification describing a design for School-Furniture, invented by ISAAC S. WACHOB, of Scranton, in the county of Luzerne and State of Pennsylvania.

The nature of my design is fully represented in the accompanying photographic illustration, to which reference is made.

In said photograph is shown the outside of one of the castings that form the end of a seat and desk combined. At the top of said casting, on the lattice-work that, with its border, makes up the end of the desk, is an arch, *a*, having a key-stone, *c*, imposts *e*, and a chord, *i*, all in bass-relief. At the middle part of the casting, between the lattice-work and the legs, is a chain, *m*, in bass-relief, having two branches,

m', at its upper end, the extremities of which branches and the lower end of the chain are attached to staples *n*. About midway of each leg, and at the point of junction therewith of the cross-piece, is a star, *o*, in bass-relief.

I claim as my invention, in a design for school-furniture—

1. The arch *a* with its key-stone *c*, as described.
2. The chain *m*, as specified.
3. The stars *o*, as set forth.

ISAAC S. WACHOB.
